2 Sheets-Sheet 2

The drawing illustrates a circular device, possibly a clock or timer, in a cross-sectional view. The top cover is labeled with numbers 1 through 15 and letters A and B. Number 1 is at the top center, 2 is at the top right, 3 is at the top left, 4 is at the bottom left, 5 is at the bottom right, 6 is at the bottom center, 7 is at the bottom right, 8 is at the top left, 9 is at the top center, 10 is at the top left, 11 is at the top right, 12 is at the top left, 13 is at the top right, 14 is at the top right, 15 is at the top right, and 20 is at the top right. Letter A is on the left side, and letter B is on the right side. The internal mechanism includes a dial with markings 24, 23, 22, 21, 20, 19, 18, 17, 16, 15, 14, 13, 12, 11, 10, 9, 8, 7, and 6. A small rectangular component is labeled with the letter P.

UNITED STATES PATENT OFFICE.

GEORGE EUGENE MITTINGER, OF CLEVELAND HEIGHTS, OHIO.

METAL KEG.

Application filed January 26, 1923. Serial No. 615,156.

To all whom it may concern:

Be it known that I, GEORGE E. MITTINGER, a citizen of the United States, residing at Cleveland Heights, Cleveland, in the county 5 of Cuyahoga and State of Ohio, have invented certain new and useful Improvements in Metal Kegs, of which the following is a specification, reference being had therein to the accompanying drawing.

10 This invention relates to improvements in metal kegs, and more particularly to a head and cover for a metal keg which is primarily adapted as a metallic container for transporting bolts, rivets and nails, to take 15 the place of the ordinary wooden keg that is now used for that purpose.

The particular adaptation of my improved head and cover, as shown in the accompanying drawings, is for use with a metallic keg 20 of a knock-down construction, which is composed of a plurality of interlocking staves, whereby when the keg is shipped in a knocked-down state, the parts thereof can be placed in nestled relation to reduce the 25 space it will assume in a freight car, or the like, and can be quickly assembled by the user as the need may arise.

Although, I have shown and described 30 my novel construction of head and cover for use with a knock-down container of a construction similar to that set forth in my pending application Serial No. 555,989, filed April 22nd 1922, I wish it to be understood that my invention can be used with containers of a different construction, without departing from the spirit and scope of my invention.

I have found that where a container is 40 entirely assembled with the exception of the head, that it will be sprung out of shape as the container is filled with any heavy material and that due to this springing of the container, it will be impossible to put the head on the same after it has been filled.

45 One of the objects of my invention is to overcome the springing or wrenching of the container out of its normal shape during the process of filling or loading it.

Another object of my invention is to provide a container head and cover therefor having novel features of construction, which 50 will be hereinafter more specifically pointed out.

A further object of my invention is to 55 provide a container head and cover therefor, constructed in such a manner that either

the head or the cover, or both, may be removed from the container as desired.

Still another object of my invention is to provide a container head having therein an 60 opening which is closed by a two-part cover.

Another and further object of my invention is to provide a container head having an 65 opening therein and being of a novel construction whereby the head will receive and retain a two-part cover, having novel features of construction whereby the cover parts are locked one to the other and to the container head.

Other and further objects, improved results, and novel features of construction of my invention will appear in the following description and accompanying drawings.

In the drawings:—

Figure 1 is a perspective view of a container showing the application thereto of my improved container head.

Fig. 2 is a fragmentary perspective view of the container showing the application thereto of my improved container head with 80 the two-part cover being applied thereto.

Fig. 3 is a fragmentary vertical sectional view of a container showing the application of my improved head and cover thereto.

Fig. 4 is an enlarged fragmentary vertical 85 sectional view showing the manner of locking the two parts of the head cover to each other.

Heretofore, containers have been provided with a complete head which is removable for the purpose of filling the same. A container having a construction of this nature is subject to the springing and wrenching action above referred to, which renders it very difficult and practically impossible 90 to apply the head to the container after the same has been filled. I have provided a construction which overcomes this undesirable feature and additionally provided a construction whereby the container will not

100 break under the rough usage it would receive and will also stand being thrown from or dropped from a considerable height without tearing apart. The construction of the container's side sections which lend to 105 the device this strength have previously been described in a previous application hereinbefore mentioned. The construction and novel features of my container head

110 and cover which also permit the keg to receive the rough usage just spoken of will now be described.

Referring now to the drawings, in which like parts are designated throughout the drawings by similar reference numerals, A represents the container sides, B the container head, and C and D the two parts of the container head and cover.

The container sides A, to which my improved head and cover are shown applied, has a plurality of upwardly projecting 10 tongues or beads 5.

My improved container head B is, in reality, a ring which has a downwardly projecting circumferential outer flange 6, topped by an upper edge 7, and approximately paralleled by an inner downwardly extending wall 8. The container head B terminates at its inner edge in a backwardly bent or rolled U-shaped circumferential groove 9, which surrounds the opening 10 in the head.

The top edge 7 of the container head B is provided with a plurality of openings 11, to receive the upwardly extending tongues 5 of the container sides A.

As will be readily understood, the head B is lowered upon the upper ends of the container sides A, in such a manner that the tongues 5 will protrude through the openings 11 of the head. The flange 6 and the inner wall 8 of the head will parallel the inner and outer sides of the container sides and the tongues 5 will be bent downwardly and inwardly, as clearly appears in Figs. 1 to 3 of the drawings, and thus lock 35 the head in place upon the container.

The head covers C and D each compose a half circle and when in place upon the head will completely close the opening 10 therein. Each of the head portions C and 40 D comprises a bottom 13, having a surrounding upstanding wall 14, terminating in a flat upper edge 15 having a downwardly and inwardly bent edge 16, which forms, when the two halves of the cover are 45 united, a circumferential U-shaped groove upon the under side of the upper edge 15 of the cover, as clearly appears.

The head covers C and D are placed upon the head in the manner shown in Fig. 2 of 50 the drawings, with the U-shaped groove of the covers engaging and sliding upon the U-shaped groove 9, of the head B. These interlocking grooves will hold the head covers in place upon the head and it remains now only to lock the two cover portions 55 one to the other.

The cover C is provided at the inner edge of its bottom with a vertically up-standing edge or wall 17, which extends completely 60 across the cover, as clearly appears in Figs. 2 and 4 of the drawing. These same figures show the inner edge of the bottom of the cover-portion D, provided with a U-shaped channel 18, extending entirely across the width of this cover.

As the two cover portions are slid upon the U-shaped groove 9 of the head towards each other, the up-standing wall 17 of the cover portion C abuts the vertical wall 19 of the U-shaped channel of the cover portion D, and the bottom of the cover portion C is supported upon the bottom 20 of the U-shaped channel 18 of the cover portion D. To lock the two cover portions one to the other, it remains only to bend or crimp the 70 top 21 of the U-shaped channel 18 downwardly over the vertical wall 17 of the cover-portion C, as clearly appears in Fig. 4 of the drawing.

Attention is directed to the fact that the head B is bent upwardly as at 22, so that when the covers C and D are in place upon the head, their upper edges 15 will be approximately in the same plane as the upper edge 7 of the head. This construction is provided so that the kegs or containers can be readily stacked one upon the other.

It may be desired to provide a sealing means for the two head portions C and D, and to provide for this, I have slit the top 90 21 of the channel 18, as at 22, and have provided intermediate these slits a cut-out portion 23. The wall 17 of the head C is provided with an opening 24 and the vertical wall 19 of the channel 18 is provided with an opening 25. It will be readily apparent that when the top 21 of the channel 18 is bent downwardly between the slits 22 therein, that a wire carrying a seal, or some similar sealing means, can be passed through the 95 openings 24 and 25 in the walls 17 and 19 respectively of the cover portions, and thus seal them together to prevent unlawful tampering with the contents of the container.

It will also be readily understood that this sealing could be utilized without providing the slits 22 and having only in the top 21 of the U-shaped channel the cutout portion 23, so that when the top 21 is bent downwardly, the sealing member could be passed through the 100 openings, as previously described.

With the slits 22 provided, the container head portions can be sealed before they are 115 locked together by bending down the entire length of the top 21 of the U-shaped channel 18. Occasions may arise where it would be desirable to seal the container and yet not lock the head portions together.

I wish it to be clearly understood that my head cover construction is not at all limited to the use of knock-down or sectional containers. My construction can be adapted to be used with containers of different constructions without departing from the spirit 125 or scope of my invention.

A container head and cover constructed in accordance with my invention has proven to have great strength and when the parts are 130 in position a loaded container can be

dropped from a considerable height and the head and cover remain intact. In addition it will be readily understood that the head B is put in place upon the container before the 5 same is loaded or filled, and that the head will prevent the springing of the container as the same is filled, thus overcoming the serious objection hereinbefore spoken of. It remains then, when the container is loaded, 10 merely to slip the cover portions in place and lock them to have the container ready for shipment.

Attention is also directed to the fact that in removing the contents from the container, 15 after the cover portions have been removed, there are no rough or jagged edges to cut the hand or wrist as it is inserted into the container. It will also be readily apparent that should the desire or necessity arise, the 20 head B, in addition to the cover portions C and D, can be removed from the container when it is desired to empty the same, and for some reason the opening 10 in the head is not sufficiently large.

25 I have shown and described my construction of container head and cover as applied to only the top of the container. Ordinarily, a solid head cover would close the bottom end of the container. Should it be desired, a 30 container head and cover construction, constructed in accordance with my invention, could be used on both ends of the container.

Attention is directed to the fact that the top 21 of the U-shaped container 18 has a 35 slight downward slant or taper as clearly appears in the drawing. The purpose of this construction is that this top will be more easily bent downwardly to lock the vertical wall 17 in place by means of a pair of 40 pinchers or some similar tool.

It will also be readily apparent that the interlocking connection between the covers C and D lie wholly within the depressed bottoms of these heads so that the top of the 45 U-shaped channel is practically in the same plane as the top of the covers and therefore in no way impair the stacking of one container upon another. Should this interlocking connection extend above the top of the 50 head covers the containers would not stack level one upon another.

Having thus described my invention, what I claim and desire to secure by Letters Patent is:

55 1. An enclosure for containers or the like, comprising a head having an opening therein, a transversely divided two-part cover having its periphery adapted to lock with the head, and the inner edges of the cover parts having up-standing projections adapted for interlocking connection of the cover parts.

60 2. In a container or the like, an end closure comprising a removable head having an opening therein, a transversely di-

vided two-part cover for closing said opening, means to lock the head to the container, and means to lock the cover parts to the head and to each other.

3. In a container or the like, a removable head having a central opening therein, a transversely divided cover for closing the head opening, the head locked to the container by means of up-standing ears beyond the container bent downwardly upon the 75 head, and the head cover slidably locked in relation with the head, for the purpose described.

4. In a container or the like, a head having a central opening provided with a 80 groove, a cover for closing said head opening, and means carried by the cover to slidably engage the said head groove to lock the cover upon the head, for the purpose described.

5. In a container or the like, a head having a central opening therein surrounded by a groove, a cover for closing the said head opening, the cover comprising two-parts 90 each of which is provided with slidable means to engage the head groove to retain the cover parts in place upon the head, for the purpose described.

6. In a container or the like, a head having a central opening therein, a transversely divided two-part cover for closing the head opening, the head and the cover parts having grooves adapted to engage for the purpose of holding the cover upon the head, 95 and means to lock the cover parts to each 100 other.

7. A cover for a container or the like, comprising two semi-circular parts, one of said parts having a vertical wall at its inner edge, the other part having a U-shaped 105 channel at its inner edge adapted to receive the vertical wall of the other part, and the top of the U-shaped channel bent downwardly to lock the said vertical wall within the channel, for the purpose described.

8. In a container or the like, a removable head having a central opening therein, up-standing ears upon the container end adapted to pass through openings in the container head and engage the head to retain it in place upon the container, a two-part cover for closing the container head opening, the cover parts in sliding locking engagement with the head, and means to lock the cover parts one to the other when they are in position to close the said head opening.

9. In a container or the like, a head having a central opening therein, a transversely divided two-part cover for closing said head opening, and the cover having sliding interlocking connection with the head, for the purpose described.

10. In a container or the like, a head having a central opening therein, a transversely divided two part cover for closing said 130

1
head opening, and the peripheries of the head opening and the cover having interlocking connection, for the purpose described.

5 11. In a container or the like, a head having a central opening therein, a cover for said head opening, and the peripheries of the head opening and the cover bent to form channels adapted for sliding interlocking
10 connection, for the purpose described.

12. In a container or the like, a head having a central opening therein, a two part cover for closing said head opening, and the inner edges of the cover parts having up-
15 standing projections adapted for interlocking connection of the cover parts, for the purpose described.

13. In a container or the like, a head having a central opening therein, a transversely

divided two-part cover for closing said head opening, sliding interlocking connection between said cover and head, and the parts arranged whereby the outer top edge of the head and the top of the cover are in the same plane whereby one container can be 20 stacked upon another.

14. In a container or the like, a head having a central opening therein, a two part cover for closing said head opening, the cover parts provided with a central de-
30 pressed portion, an interlocking connection between the cover parts wholly within said depressed portion of the cover parts, whereby the containers can be stacked one upon another.

In testimony whereof I hereunto affix my signature.

GEORGE EUGENE MITTINGER.
